UNITED STATES PATENT OFFICE.

JOHN WICKS, OF OAK PARK, ILLINOIS, ASSIGNOR, BY MESNE ASSIGNMENTS TO AUTOMATIC ELECTRIC INC., OF CHICAGO, ILLINOIS, A CORPORATION OF DELAWARE.

TELEPHONE SYSTEM.

Application filed March 2, 1925. Serial No. 12,472.

The present invention relates to telephone systems in general, but is concerned more particularly with telephone systems employing automatic switches for completing connections, and is concerned still more particularly with a telephone system covering an area which is more or less thickly populated and is served by means of a number of small automatic exchanges, one for each community, known as "community automatic exchanges", with a more or less centrally located manual exchange serving as a toll center through the medium of which the various community automatic exchanges are linked with each other and with trunk toll lines.

As is generally known, the ordinary two-wire system of operation, in which the automatic switches are controlled over the two sides of the line in series, is not applied unchanged to toll line operation. There are a number of reasons for this, among which are the following: One reason for the change is on account of the fact that, since in a straight two-wire system, the line relays of the automatic switches must be controlled through a resistance equal to the sum of the resistances of the separate conductors comprising the line and the associated telephone apparatus, and the toll lines (which are usually long as compared to the local lines and trunk lines to which two-wire operation is applied) are too long for straight two-wire operation. Another reason for using some scheme other than the straight two-wire operation is found whenever the toll lines are associated in pairs for the purpose of forming phantom circuits.

According to the foregoing, in the case of a single toll line, arrangements are made for transmitting the talking current over the two sides of the line in series and for operating the automatic switches over the two sides of the line in multiple with an earth return.

Similarly, in the case of a phantomed pair of physical lines, the three talking circuits thus secured are extended on the distant end by a like number of automatic switches which are controlled over three of the four possible so-called "Morse" circuits which are obtained by the well known method of using balancing coils and condensers,

as is so often done in case Morse telegraph systems are used in conjunction with telephone lines.

The foregoing serves to illustrate what is meant by the switch control circuit as distinct from the talking circuit and serves, therefore, to clarify the following statement of the objects and features of this invention.

One object of the invention is the production of circuit arrangements enabling the control of the signalling (ringing) to be carried out in either direction over a toll line through the medium of the switch control circuit rather than over the talking path itself.

Specifically, one object of the invention is the provision of circuit arrangements whereby the ringing current itself is transmitted over the control circuit on calls from a community automatic exchange (abbreviated as C. A. X.) to the toll center, together with the provision of circuit arrangements for cutting off the ringing current when the operator responds and for connecting the control circuit to the supervisory branch at the C. A. X.

Another object is the provision of circuit arrangements whereby on calls from the toll center to a C. A. X. the starting of the ringing operation (which is arranged so as not to start automatically upon the completion of a toll connection) is placed under the control of the toll operator at the toll center who controls the starting of the ringing operation over the control circuit.

Another object of the invention is the provision of greatly simplified circuit arrangements for controlling the ring cut-off relay of a connector switch from the selector repeater, which consists in an arrangement for utilizing the action of the switching relay of the connector to obviate the use of an added relay, together with suitable cooperating arrangements in the selector repeater.

The other objects and the various features not here mentioned will appear from a perusal of the description.

Referring now to the drawings comprising Figs. 1-3, they show by means of the usual circuit diagrams a sufficient amount of apparatus in a system embodying the features of

the invention to enable the invention to be understood and its utility to be appreciated.

The equipment shown in Fig. 1 is located in the toll center, i. e., the manual office 5 through which the toll calls are closed, and Figs. 2 and 3 show apparatus in one of the community automatic exchanges.

Referring now particularly to Fig. 1, this drawing shows a cord circuit CC at an operator's switchboard, together with the jack J associated with the two-way toll line TL leading to the community automatic exchange shown in Figs. 2 and 3. This drawing shows also the supervisory signal S and the drop 15 signal D, together with the common calling device CD.

Fig. 2 shows the selector repeater SR, through which calls coming in to the C. A. X. over toll line TL are completed.

20 Fig. 3 shows the connector C, which is accessible to the selector repeater SR, and which has access on one level to the toll line TL and others, having access to the toll line TL through conductors 127—129. The connector C has access on the other levels to the lines of local subscribers. The connector C is accessible to local selectors as may be seen in Fig. 2.

Regarding the mechanical construction of 30 the selector repeater SR and the connector C, it may be pointed out that these switches are of the usual vertical and rotary type and accordingly their bank contacts are arranged in horizontal rows or levels.

35 The booster battery BB, Fig. 1, is a battery of dry cells, which may be used economically on account of the slight current drain.

40 The apparatus having been described generally, it will now be assumed that the operator at the toll center is informed of a toll connection which is desired by the subscriber at substation A, whose line terminates at the C. A. X., shown in Figs. 2 and 45 3. That being the case, the operator inserts a plug of an idle cord circuit, for example, the plug P of the cord circuit CC into the jack of an idle toll line, for example, the jack J of the toll line TL. When this occurs, the tip and ring conductors of the cord circuit CC are connected to the corresponding talking conductors of the jack J. Also the spring 2 of the jack J is operated to disconnect the operating conductor 13 from 55 the drop D and to connect it to battery through contacts of the key K and the supervisory signal S, whose right hand terminal is connected to the exchange battery EB through the jumper between terminals 10 and 12. Conductor 13 is connected to the junction of the right hand windings of the repeating coil on the toll-center end of the trunk line TL. The junction of the left hand windings of the repeating coil on the 60 C. A. X. end of the toll line TL is normally

grounded through the operating conductor 101, armature 142 and its resting contact, armature 146 and its resting contact, marginal ringing-control relay 105, line relay 107, common conductor 132, and the jumper 70 131. Accordingly, a circuit is established from the grounded exchange battery EB in the toll center over the operating conductor to ground in the C. A. X. Since this circuit includes the supervisory signal in the toll 75 center, this signal operates.

In the C. A. X., line relay 107 pulls up responsive to the establishment of the above mentioned control circuit over the two sides of the toll line TL in parallel, but the marginally-adjusted ring-control relay 105 does not operate at this time. Upon operating, line relay 107 closes at armature 150 a circuit for the release relay 108, which energizes and at armature 152 opens a point in the circuit of release magnet 126 and prepares a circuit for vertical magnet 121. At armature 151, release relay 108 places ground on conductor 130, thereby preparing a subsequently closed circuit for switching relay 111 and closing a circuit for the polarizing winding of the electro-polarized relay 102. This winding is composed of a comparatively small number of turns of wire having a relatively high resistance. Accordingly, relay 102 does not operate at this time.

As a further result of its operation, line relay 107 closes at armature 170 a circuit to ground through the right hand repeating coil windings for the dial tone current, with the result that the dial tone is heard by the calling operator.

50 In the toll center, the operator (assured by the dial tone that the distant selector repeater is ready to be operated) now throws the key K into dialling position, thereby connecting the calling device CD, whose lower terminal is connected to battery, to the control conductor 13 in place of the signal S. Accordingly, the supervisory signal S restores.

The operator now manipulates her calling device CD in accordance with the first digit in the desired number. When she does so, the control circuit is interrupted a corresponding number of times with the result that line relay 107 of the selector repeater SR, Fig. 2, falls back each time the control circuit is interrupted. Each time it deenergizes, line relay 107 closes at armature 150 a circuit through armature 152 and its working contact, series relay 109, and armature 158 and its resting contact for vertical magnet 121. By the operation of vertical magnet 121, the wipers 162—165 are raised step by step and come to rest opposite the desired level of bank contacts. Relay 109 is energized in series with vertical magnet 121 and, being slow acting, maintains its armature 120 125 130 135 140 145 150 155 160 165 170 175 180 185 190 195 200 205 210 215 220 225 230 235 240 245 250 255 260 265 270 275 280 285 290 295 300 305 310 315 320 325 330 335 340 345 350 355 360 365 370 375 380 385 390 395 400 405 410 415 420 425 430 435 440 445 450 455 460 465 470 475 480 485 490 495 500 505 510 515 520 525 530 535 540 545 550 555 560 565 570 575 580 585 590 595 600 605 610 615 620 625 630 635 640 645 650 655 660 665 670 675 680 685 690 695 700 705 710 715 720 725 730 735 740 745 750 755 760 765 770 775 780 785 790 795 800 805 810 815 820 825 830 835 840 845 850 855 860 865 870 875 880 885 890 895 900 905 910 915 920 925 930

attracted throughout the vertical operation. As a result of the energization of relay 109, a circuit is closed at armature 154 from the grounded conductor 130 for stepping relay 110. Stepping relay 110 accordingly energizes; prepares a circuit at armature 155 for rotary magnet 124; and at armature 156 closes a point in its locking circuit, which is completed through the interrupter contacts 123 as soon as the off normal contacts 122 close, as they do upon the first vertical step of the switch.

At the end of the vertical movement, the slow acting series relay 109 falls back and 15 closes the rotary magnet circuit, at the same time opening the initial circuit of stepping relay 110, leaving stepping relay 110 energized through its locking circuit. The rotary magnet 124 now energizes from the 20 grounded conductor 130 through the normally closed contacts controlled by armature 154 and through armature 155 and its working contact, and advances the wipers of the switch into engagement with the first set of 25 bank contacts in the called level. Near the end of its stroke, rotary magnet 124 opens the circuit of relay 110 at the interrupter contacts 123, whereupon relay 110 falls back and opens a further point in its locking circuit at armature 156 and at armature 155 30 opens the circuit of the rotary magnet 124 which deenergizes also. At contacts 123, the stepping relay 110 is again connected up through the resting contact and armature 159 35 to the test wiper 154.

The further operation depends upon whether the trunk terminating in the first set of bank contacts is busy or idle. If it is idle, switching relay 111 is not effected by 40 the test wiper 164 on account of the fact that the latter engages an ungrounded bank contact, and switching relay 111 energizes, seizing the trunk.

Assuming, on the other hand, that the 45 trunk is busy, test wiper 164 encounters ground on the busy test contact and a circuit is closed through armature 159 and its resting contact, interrupter contacts 123, and off normal contacts 122 for the stepping 50 relay 110 which energizes; closes a locking circuit for itself at armature 156; and at armature 155 closes a circuit for rotary magnet 124 which thereupon energizes and advances the wipers into engagement with the 55 next set of bank contacts.

This alternate operation of stepping relay 110 and rotary magnet 124 continues as described until an idle trunk is reached, which trunk, it will be assumed, is the one comprising conductors 166—169 and extending to the connector C, Fig. 3.

When this idle trunk is reached, switching relay 111, being no longer short circuited, energizes from the grounded conductor 60 130 in series with relay 110. Stepping

relay 110 does not operate at this time, however, on account of the relatively high resistance of switching relay 111. Upon energizing, switching relay 111 opens a point in the locking circuit of stepping relay 110 70 at armature 160 and grounds wiper 163 through relay 106, normally closed contacts controlled by armature 148, and the resting contact and armature 147. Relay 111 also opens the vertical and release magnet circuits at armature 158, and at armature 159 disconnects test wiper 164 from the test circuit and connects it to the grounded conductor 130, thereby placing ground on release trunk conductor 168 to make the seized 80 trunk busy immediately. At armatures 157 and 161, relay 111 disconnects the right-hand repeating coil windings from ground and the dial tone lead and connects them to wipers 162 and 165. Accordingly, line relay 202 of the connector C, which is connected to conductors 166 and 169 through the normally closed contacts controlled by armatures 221 and 222 of back bridge relay 201, now pulls up over the bridge including the lower 85 winding of the electro-polarized relay 102 of the switch SR. The electro-polarized relay 102 of the selector repeater SR does not operate at this time, owing to the fact that the current flow in its lower winding is in 90 such a direction so as to oppose the effect of the current flow in the upper winding.

In the connector C, release relay 203 energizes responsive to the closure of its circuit by line relay 202; prepares an energizing circuit for switching relay 210 and a locking circuit for busy relay 207 at armature 225; opens a point in the release magnet circuit and prepares a point in the operating circuit at armature 226; and at armature 224 places ground on release trunk conductor 168, so as to establish the usual holding circuit for the preceding switch and so as to maintain the connector busy. This, however, does not have any particular utility at this time, owing to the fact that the preceding switch is a selector repeater and not an ordinary selector. Accordingly, the release trunk conductor 168 is maintained 100 grounded by the switch SR and the switch C 105 also.

Responsive to the above mentioned grounding of wiper 163 of the switch SR through the marginal relay 106, ground is extended over conductor 167 and armature 110 115 259 and resting contact to the upper winding of relay 205, which energizes and locks up at armature 229 to conductor 168. The marginal relay 106 does not operate at this time on account of the fairly high resistance 120 of the circuit.

When the operator dials the next digit in the desired number, line relay 107 of the selector repeater SR deenergizes a corresponding number of times as before. No 130

circuit, however, is closed for vertical magnet 121 of the switch at this time, on account of the fact that this magnet is disconnected at armature 158 of switching relay 111. Responsive to each deenergization of relay 107, the bridge across the conductors 166 and 169 of the trunk extending to the connector C is opened at armature 17, whereupon line relay 202 of the connector C deenergizes. The result is that line relay 202 is deenergized once for each opening of the circuit at the operator's calling device.

Each time line relay 202 of the connector C falls back, it closes at armature 223 a circuit for vertical magnet 214, the circuit at the time of the first closure including armature 226 and its working contact, contact of off normal spring 213 and said spring, and the slow acting series relay 204. By 20 the operation of vertical magnet 214, the wipers 246—249 are raised step by step and come to rest opposite the desired level of bank contacts. Relay 204 is energized in series with vertical magnet 214 upon the 25 first impulse of current being delivered to the latter, and, being slow acting, maintains its armature 227 attracted throughout the vertical movement, thereby maintaining its own circuit and that of vertical magnet 214 30 closed through the normally open contacts controlled by off normal spring 213 and armature 227 and its working contact, after the off normal springs have shifted, as they do upon the first vertical step. At the end 35 of the vertical movement, relay 204 falls back and transfers the operating circuit from the vertical magnet to the rotary magnet.

When the operator turns her calling device for the next and last digit in the desired number, the resulting impulses of current transmitted in response to the deenergizations of relay 202 of the connector C are transmitted at armature 223 and its resting 40 contact, through armature 226 and its working contact, normally open contacts controlled by off normal spring 213, armature 227 and its resting contact, armature 234 and its resting contact, series relay 208, and 45 armature 244 and its resting contact to rotary magnet 215. Rotary magnet 215 responds to these impulses and advances the wipers 246—249 into engagement with the bank contacts in which the line of substation A terminates. It will be noted that 50 the slow acting relay 209 is normally in multiple with magnet 215. Accordingly, relays 208 and 209 both energize over the operating circuit upon the first impulse of current delivered to magnet 215. Relay 208 disconnects busy relay 207 at armature 237, so as to prevent its premature energization, and at armature 238 closes a local circuit for 55 relay 209 and disconnects it from the operating circuit, so that relay 209 will not

start to become deenergized until relay 208 has fallen back at the end of the rotary movement. Relay 209, upon energizing, closes at armature 240, a point in the circuit of the stepping relay 206, and at armature 70 239 disconnects test wiper 247 from the test winding of relay 210 and prepares a path for connecting the test wiper 247 to busy relay 207 upon the subsequent deenergization of relay 208.

At the end of the rotary movement, relay 208 falls back and connects busy relay 207 to test wiper 247 at armature 237 through the working contact and armature 239, and at armature 238 opens the local circuit of relay 209 and connects it to the operating circuit again. Relay 209, however, does not fall back immediately, on account 80 of the fact that it is slow acting.

It may be pointed out here that the operator, having dialled the number, now restores her dialling key K, whereupon the supervisory signal S becomes operated again.

The further operation depends upon whether the called line is busy or idle. If it 90 is busy, busy relay 207 is energized from the ground potential encountered by test wiper 247 on the grounded test contact. At armature 235, relay 207 connects stepping relay 206 to the rotary test wiper 248. Relay 95 206, however, does not energize at this time, even though the called line is busy, because the rotary test contact 253 is not jumpered to the regular test contact 252. These two contacts are not connected because the line 100 of substation A is an ordinary line and not a line of a group having a common destination. At armature 233, relay 207 prepares a locking circuit for itself; at armature 234 it opens the operating circuit; and 105 at armature 236 it connects up the common busy signalling lead to the lower heavy talking conductor.

After an interval which is sufficiently long 110 to permit the automatic rotary movement to start, in case such movement is to take place, relay 209 falls back and disconnects relay 206 from the rotary test wiper 248 at armature 240, and at armature 239 it disconnects test wiper 247 from busy relay 207 and connects it again to the upper winding of 115 stepping relay 210. The locking circuit of busy relay 207, which includes the working contact and armature 225 of release relay 203, armature 233 and its working contact of busy relay 207, normally closed contacts controlled by armature 239, and the resting contact and armature 237, is completed at the normally closed contacts 120 controlled by armature 239. Accordingly, busy 125 relay 207 remains locked up over a local circuit and at armature 233 maintains the upper terminal of the test winding 210 disconnected from ground.

As a result of the connection of the com- 130

mon busy signalling conductor to the lower heavy talking conductor, a busy tone is transmitted back to the calling operator to inform her that the desired line is, for the

5 time being, inaccessible. In this case, the operator pulls down the connection and calls again later.

It will be assumed now that the line of 10 substation A is idle when called. In this case, test contact 252 is not grounded when the wipers of the connector C land upon the bank contacts of the called line, and busy relay 207 does not, therefore, energize when it is connected up to wiper 247 at armature 15 237. Under this condition, when relay 209 deenergizes, it completes at armature 239 a circuit for the test winding of switching relay 210 as follows: From ground by way 20 of the working contact and armature 225, armature 233 and its resting contact, upper winding of switching relay 210, resting contact and armature 239, wiper 247, bank contact 252, switching relay 261 of the line switch LS, and stepping magnet 263 to 25 battery. Switching relays 210 and 261 energize in series over this circuit. Relay 261, however, operates only about half way on account of the usual interlocking device between its armature proper and that of the 30 associated line relay 262. Therefore, the wipers of the line switch are not connected up.

In the connector C, switching relay 210, upon energizing, closes at armature 243 a 35 locking circuit for its lower winding; places direct ground on test wiper 247 at armature 242; disconnects rotary magnet 215 and relay 209 from the operating circuit at armature 244; disconnects conductor 167 from 40 the left hand terminal of the upper winding of ring cut-off relay 205 at armature 259 and connects it to the right hand terminals of the same winding; and at armatures 241 and 245 connects up the line wipers 45 246 and 249.

The shifting of conductor 167 from the left-hand terminal to the right-hand terminal of the locking winding of relay 205 results in the operation of the marginal relay 106 of the switch SR, Fig. 2, because 50 the resistance of the locking winding of relay 205 is excluded from the circuit of relay 106. Upon operating, relay 106 locks itself to battery, at armature 148, through the associated resistance and disconnects itself from wiper 163. At armature 149, relay 106 connects the common lead from the battery interrupter 133 through the resting contact and armature 141 to the operating circuit 55 at the junction of the windings of relays 105 and 107. Accordingly, each time battery is placed on the associated common conductor by the interrupter 133, current ceases to flow over the portion of the 60 control circuit extending to the toll center 65

and the signal S falls down, to operate again when the interrupter 133 opens again. This action of the signal S informs the operator that the line is seized.

The connection is now extended to the line 70 of substation A and it merely remains for the operator to bring about the deenergization of ring cut-off relay 205 (which relay is locked up to conductor 168 at armature 229) of the connector C, so as to project 75 ringing current out over the called line to signal the called subscriber. Before doing this, the operator extends a connection to the desired line through the medium of the other plug (not shown) of the cord circuit CC, 80 Fig. 1. When the desired subscriber answers, he is told that he is wanted in a toll connection and is told to wait for the calling party who will now be signalled. The operator now throws the key K into ringing 85 position, thereby connecting the booster battery BB (in series with the regular exchange battery EB) to the operating conductor 13 through the upper contact and springs 2, instead of the exchange battery alone 90 (through the supervisory signal S). Accordingly, the current flow over the control circuit during the open periods of the interrupter 133, Fig. 2, is very much increased. As a result, the marginal ringing control 95 relay 105 in the selector repeater SR energizes in series with line relay 107, and at armature 147 grounds wiper 163. When this occurs, the locking winding of relay 205, Fig. 100 3, is short circuited and the relay falls back. At armatures 228 and 230 relay 205 disconnects wipers 246 and 249 from the windings of back bridge relay 201 and connects them instead to the ringing circuit. Ringing current is now intermittently projected 105 through the common ringing conductor, jumper 271, resting contact and armature 230, and the lower talking conductor to the substation A to operate the bridged bell thereat, and it returns by way of the upper talking conductor to ground through the jumper 273, lower winding of relay 205, and jumpers 272 and 217.

After holding her ringing key K, Fig. 1, operated for a short interval, the operator 115 restores this key, thereby restoring the control circuit to the exchange battery EB through the supervisory signal S. The signal S resumes its up and down operation under the control of the interrupter 133, 120 Fig. 3.

When the ringing key is restored, relay 105 in the C. A. X. falls back and removes ground from conductor 163, so as to permit the ring cut-off relay 205 to lock up as soon 125 as the subscriber at substation A responds.

When the subscriber at substation A responds to the ringing of his bell by removing his receiver, a direct current bridge is placed across the conductors of his line, 130

whereupon ring cut-off relay 205 energizes over the ringing circuit. Upon energizing relay 205 again locks itself to conductor 168 at armature 229, and at armatures 228 and 230 disconnects the wipers 246 and 249 from the ringing circuit and extends them to the windings of back bridge relay 201. Back bridge 201 now energizes over the line of substation A and at armatures 221 and 222 10 reverses conductors 166 and 169 as regards their connection with the windings of line relay 202. This results in a reversal in the direction of current flow in conductors 166 and 169 and consequently in the lower 15 winding of the electro-polarized relay 102, Fig. 2. Accordingly, relay 102 responds by attracting its armature 141, thereby disconnecting the interrupter lead 119 from the operating conductor, whereupon the supervisory signal S again operates steadily.

When the operator notes that the supervisory signal S is no longer alternately displaying and restoring, she knows that the calling subscriber has responded, and she, 25 therefore, throws her listening key and informs the subscribers that the connection is now completed.

The two subscribers may now converse with each other as desired.

30 When the conversation is completed, the two subscribers replace their receivers.

When the receiver is replaced as substation A, back bridge relay 201 of the connector C falls back and reverses the conductors 166 and 169 back to normal, whereupon 35 the electro-polarized relay 102 of the selector repeater SR falls back and again connects up the interrupter lead 190 to the operating conductor at armature 141. When 40 this occurs, the supervisory signal S at the operator's switchboard starts to energize and deenergize again under the intermittent short circuiting influence of the interrupter I in the C. A. X.

45 The operator recognizes this operation on the part of the supervisory signal S as the disconnect signal and she accordingly removes the plug P from the jack J, thereby disconnecting the operating conductor 13 from battery through the supervisory signal 50 S and connecting it up to the drop D again.

When this occurs, relay 107 in the C. A. X. falls back as soon as the interrupter I permits and opens the circuit of release relay 55 108 at armature 150 and opens the circuit of line relay 202 of the connector C at armature 170. Responsive to the opening of its circuit at armature 150, relay 108 deenergizes, it being arranged, of course, so that 60 the interrupter I operates slowly enough to permit relay 108 to fall back before it again operates relay 107.

Upon deenergizing, relay 108 removes ground from conductor 130 at armature 151, 65 leaving the said conductor grounded by way

of wiper 164 from the connector C provided the release relay thereof has not yet fallen back. At armature 152 relay 108 closes a point in the release magnet circuit. Relay 108 also renders the trunk line accessible 70 again at armature 153 to the local connectors.

As soon as conductor 168 is ungrounded in the connector C, relay 111 of the switch SR deenergizes and opens at armature 160, the 75 circuit of relay 106 which deenergizes and disconnects the interrupter lead 119 from the operating conductor 101 at armature 149. Release magnet 126 now energizes through armature 158 and restores the switch to its 80 normal position, whereupon the circuit of the release magnet is opened at off normal contacts 125.

In the connector C, when release relay 203 falls back responsive to the deenergization 85 of line relay 202 and removes ground from conductor 168 at armature 224, relays 205 and 210 fall back. At armature 226, relay 203 closes a circuit through off normal contacts 212 for release magnet 211, with the result that the switch is restored to its normal position in the usual manner.

The foregoing description sets forth the operation when the toll operator recalls the subscriber at substation A on a call originated by him without describing how the subscriber at substation A is able to get in touch with the toll operator in the first place to inform her that he desires a toll connection. Such explanation will now be given. 100

When the subscriber at substation A desires to set up a toll connection, he removes his receiver and dials the three digits necessary to obtain connection with the toll operator.

When the receiver is removed at the substation A, a circuit is closed over the conductors of his line for line relay 262 of the line switch LS. Relay 262 energizes and at armature 284 places ground on the private 110 normal conductor extending to the connector C and the other connectors, thereby making the calling line busy to these connectors and closing a circuit through relay 261 and stepping magnet 263 in series. At armature 285, 115 relay 262 connects test wiper 287 to the junction of relay 261 and stepping magnet 263.

From this point, the operation depends upon whether the trunk upon which the wipers of the line switch are standing is busy or idle. If this trunk is idle, switching relay 261 is not affected by the operation of armature 285 and it accordingly energizes right away, seizing the trunk.

Assuming, on the other hand, however, 125 that the trunk is busy, switching relay 261 is short circuited by the ground potential encountered on the busy test contact by test wiper 287, and does not energize. Stepping magnet 263 in this case operates in a buzzer. 130

like manner and advances the wipers 286—288 in search of an idle trunk.

When an idle trunk is reached, relay 261 is no longer short circuited and energizes.

5 Stepping magnet 263 does not energize in series with relay 261 on account of the relatively high resistance of the latter. Upon energizing, relay 261 disconnects test wiper 287 from the test circuit and connects it to 70 the grounded private normal conductor at armature 282, thereby making the seized trunk busy immediately, and at armatures 281 and 283 disconnects the line conductors from relay 262 and ground and extends them 75 15 by way of wipers 286 and 288 to the line conductors of the selector (not shown) on the seized trunk line. When this occurs, the line relay of the seized selector energizes and pulls up the associated release relay, with the 20 result that the release trunk conductor is grounded to maintain the line switch LS operated and to maintain the trunk busy after the slow acting line relay 262 deenergizes.

The calling subscriber now operates his 25 calling device in accordance with the first digit in the number necessary to obtain connection with the toll operator, whereupon the seized selector raises its wipers opposite the desired level of bank contacts and rotates them in search of an idle trunk. It 30 will be assumed that the trunk comprising conductors 166, 168, and 169 and extending to the connector C is in the one seized by the selector in use. In this case, the operation 35 of the connector C, as regards its seizure and its response in accordance to the two digits is substantially the same as hereinbefore described, with the difference that, as no connection is made with conductor 40 167, the preliminary pulling up of the ring cut-off relay 205 does not take place in this case.

Owing to the fact that the subscriber is calling the number of the toll operator, the 45 wipers of the connector C come to rest in engagement with the bank contacts leading to one of the toll lines and it will be assumed that the bank contacts 255—258 are the first contacts in the group assigned to 50 the toll lines. Therefore, these contacts are the ones upon which the wipers land at the end of the directive rotary movement.

In this case, as in the case preceding, the further operation of the connector C after 55 the directive rotary movement depends upon whether the line terminating in the contacts on which the wipers are standing is busy or idle. If it is busy, wiper 247 encounters ground upon the test contact 256, and busy 60 relay 207 energizes as soon as it is connected to wiper 247 by relay 208, and at armature 235 connects relay 206 through contacts 216 and armature 240 and its working contact to the rotary test wiper 248. Test contact 65 257 is connected by means of jumper 250 to

test contact 256. Accordingly, a circuit is provided for stepping relay 206 which energizes and closes a locking circuit for itself at armature 232, and at armature 231 closes a circuit for rotary magnet 215 which accordingly energizes and advances the wipers 246—249 into engagement with the next set of bank contacts. Current also flows through relay 209, in multiple with magnet 215, thereby maintaining relay 209 energized throughout the rotary movement. Near the end of its stroke, rotary magnet 215 opens at contacts 216 the circuit of stepping relay 206, with the result that stepping relay 206 falls back and opens a point in its locking circuit at armature 232, and at armature 231 opens the circuit of rotary magnet 215. Rotary magnet 215 deenergizes and closes its interrupter contacts again, thereby again connecting relay 206 to wiper 248. In 80 case the trunk terminating in the second toll line is idle, the rotary movement now stops, but if it is busy, and if it is not the last trunk line in the group, relay 206 energizes again from wiper 248 and again closes the circuit of rotary magnet 215, with the result that the wipers are advanced another step.

This alternate operation of relay 206 and magnet 215 continues as described until an 90 idle trunk line is reached, or until the last trunk line of the group is reached. The automatic rotary movement stops in either case because no ground is then encountered by test wiper 248. 100

When an idle trunk is reached, busy relay 207 falls back, and as soon as relay 209 falls back responsive to the cessation of the automatic rotary movement, relay 210 is connected to wiper 247 and (assuming for the 105 sake of illustration that the idle trunk is the one comprising conductors 127—129) wiper 247 encounters battery through conductor 128, armature 153 and its resting contact, and relay 103. Accordingly, relay 103 110 energizes in series with switching relay 210 of the connector C and at armature 142 disconnects the control conductor 101 from line relay 107 and connects it instead to the negative conductor 129 through the lower 115 winding of ring cut-off relay 104, the normally closed contacts controlled by armature 144 and the jumper 140.

In the connector C, relay 210 energizes over the above traced circuit and, in addition to performing the other functions described hereinbefore, connects up the line wipers at armatures 241 and 245. Ringing current is now projected out over the ringing lead through the negative wiper 249 to 120 the selector repeater SR by way of conductor 129, and from thence through jumper 140, the normally closed contacts controlled by armature 144, lower winding of relay 125 104, and the working contact and armature 130

142, to the control conductor 101. This ringing current passes over the two sides of the toll line in multiple and reaches the control conductor 13 in the toll center and then 5 goes through spring 2 and its lower contact and by way of the condenser 3 to the drop D. The drop D responds to the ringing current and releases its indicator, thereby informing the operator of the call.

10 When the operator notes the released condition of the drop D, she inserts the plug of an idle cord circuit, for example, the plug P of the cord circuit CC into the jack J, whereupon the control conductor 13 is disconnected 15 from the drop D and is connected to the exchange battery EB through the supervisory signal S. When this occurs, direct current flows from the ringing lead associated with the connector C, Fig. 3, (either 20 directly from ground or from ground through the generator) and thence out over the ringing circuit to battery in the toll center. Accordingly, relay 104 in the selector repeater SR responds to the direct current 25 and closes a locking circuit for its two windings in series at armature 144, at the same time opening the ringing circuit. The locking circuit includes the common conductor 132, the upper winding of relay 104, 30 armature 144 and its working contact, lower winding of relay 104, working contact and armature 145, the operating conductor 101, and the remaining part of the circuit, as traced, to battery in the toll center through 35 the supervisory signal S. As a further result of its energization, relay 104 disconnects the resting contact of the operated armature 142 (of relay 103) from line relay 197 and connects it instead to the interrupter lead 119 for a purpose to be explained 40 hereinafter; at armature 143 disconnects the upper talking conductor from ground and connects it instead to the negative incoming trunk conductor 127; and at armature 143' 45 connects conductor 129 to the lower talking conductor of the switch SR, thereby completing the talking circuit as regards the selector repeater SR.

In the connector C, ring cut-off relay 205 50 does not energize responsive to the insertion of the plug P into the jack J because it is not included in the ringing circuit in this case, but upon the operation of relay 104, relay 205 energizes over both wipers of the connector C in series, over conductors 127 and 129, and through the right hand repeating coil windings and the lower winding of relay 102. Relay 205 opens the ringing circuit and connects up back bridge relay 201 to the 55 wipers of the connector, whereupon relay 201 pulls up and reverses the current flow in the calling line, but this reversal has no particular function in the present case.

The electro-polarized relay 102 of the 60 switch SR, through which relay 201 operates,

does not operate at this time on account of the comparatively small number of turns on its lower winding.

The calling subscriber and the operator may now converse with each other in any 70 desired manner and the operator completes the toll connection according to local practices.

The practice employed in completing the toll calls, it will be understood, varies somewhat with different operating companies and also with different local conditions. For example, in some cases where the desired connections may be quickly set up, the calling subscriber remains on the line and the operator completes the connection right away. In other cases where the connection desired may be one that is of such a nature as to require considerable time to complete, the calling subscriber is requested to hang up his 80 receiver and wait until he is recalled, as described in the first part of this specification. 85

In any event, the subscriber at substation A finally hangs up his receiver, and when he does so, the connector C is released in the 90 hereinbefore described manner and ground is removed from conductor 128, whereupon relay 103 of the selector repeater SR falls back and at armature 142 connects the operating conductor 101 through armature 146 95 and its working contact to the interrupter 133 which places battery at intervals upon conductor 101. Upon each application of battery, the supervisory signal S, Fig. 1, de-energizes, as in the previous case, and this 100 operation attracts the attention of the toll operator, who pulls down the connection, with the result that the supervisory signal S restores and relay 104 of the selector repeater SR falls back. 105

Perhaps it may be desirable to point out briefly that local connections between subscribers in the C. A. X. are established in somewhat the same way as the connections to the toll operator in that they involve the use 110 of a selector and a connector for each call, as will be readily understood.

Certain details not particularly dwelt upon in the foregoing will now be taken up.

The first point to be taken up is the arrangement of the battery supply to the control circuit including conductors 13 and 101 at either terminal and the two conductors of the toll line TL in multiple. From the standpoint of operating the selector repeater 115 SR, the control circuit includes the line relay 107 of the selector repeater SR and is connected to a ground return both at the toll center and at the C. A. X. The only point to be considered is the position occupied by the battery in the control circuit, and possible leakage to ground along the toll line TL is about the only factor that need be considered in locating the battery in the control circuit. The battery is shown in the drawings as 120 125 130

located at the toll center and is the exchange battery EB. With the battery located at the calling device end of the control circuit, the toll line TL is electrically dead each time the 5 contacts of the calling device CD open (except for slight inductive kicks from the toll line itself and from the line relay of the selector repeater) which would not be the case if the battery were located at the opposite end of the control circuit.

The above sets forth what is considered to be the best practice in locating the battery supply to the control circuit. However, it may happen that no exchange battery is 10 available at the toll center. In this case, rather than to provide a battery along with the necessary charging apparatus, etc., arrangements are made for using the exchange battery at the C. A. X., which battery must 15 be provided in any event to operate the C. A. X. switches. That being the case, the control circuit is connected to ground at the toll center by means of a jumper connected between the terminals 10 and 11, and 20 the jumper between terminals 10 and 12 is omitted. At the C. A. X., the common return conductor 132 is disconnected from ground by cutting the jumper 131 and it is jumpered to the exchange battery instead.

25 The foregoing changes take care of the control circuit as regards the operation of the C. A. X. switches from the toll center, but, in order to secure the desired alternate display and restore action of the supervisory signal S, Fig. 1, the interrupter 133 is disconnected from battery by the cutting of jumper 130, and it is connected to ground instead.

Since the control circuit is connected to 30 ground at the toll center and, the C. A. X. ringing current must now be superimposed on battery instead of on ground as before (so as to operate relay 104 when the operator responds). In this case the ringing 35 return circuit of the connector C must be connected to ground in order to operate the ring cut-off relay 205 on local calls. Accordingly, the jumpers 217 and 218, Fig. 3, are both cut and new jumpers are inserted 40 which connect conductor 219 to ground and connect conductor 220 to battery. Also jumpers 272 and 273 are reversed at one end to maintain the same direction of current flow through the lower winding of relay 205.

In case it is not necessary to keep the polarity of the wipers of the connector C the same at all times, the above changes are sufficient, but, in case it is desired to keep 50 the polarity of the wipers of the connector C straight, it is necessary to further re-arrange the jumpers individual to the connector C so that the ringing current (which is now superimposed upon battery instead of upon ground) goes out over the negative wiper

246 and so that the ringing return lead (which is now connected to ground instead of to battery) is connected with the lower wiper 249. Accordingly, the jumpers 271, 272, and 273 are removed. A new jumper 70 is placed between the terminal associated with the resting contact of armature 228 and the terminal in which the common ringing lead terminates so as to send the ringing current out over the upper wiper 246. Two 75 other jumpers are run which connect the resting contact of armature 230 to the common return conductor 219 through the lower winding of ring cut-off relay 205. Specifically, the terminal associated with 80 the resting contact of armature 230 is connected with the left-hand terminal of the lower winding of relay 205, and the right-hand terminal of the lower winding of relay 205 is connected to the terminal in which 85 the common return conductor 219 terminates. This apparent reversal in the connection to the lower winding of relay 205 is necessary on account of the fact that the direction of the current flow in the lower 90 winding must agree with the direction of the current flow in the upper winding of the relay, which it would not do if this manner of connecting were not followed.

95 Since the ringing current is now impressed upon the negative talking conductor 127 leading to the selector repeater SR instead of upon the positive conductor 129 as heretofore, the jumper 140 connecting the lower winding of relay 104 of the switch 100 SR with the lower talking conductor 129 is cut and a jumper is inserted between the two upper terminals, thereby connecting the lower winding of relay 104 with the upper 105 talking conductor 127.

In the toll center the jumpers between terminals 6 and 8 and terminals 7 and 9, respectively, are cut and new jumpers are run between terminals 6 and 9 and terminals 7 and 8, respectively, so as to reverse 110 the battery BB to agree in polarity with the current from the C. A. X. battery.

What is claimed is:

1. In a telephone system, an automatic exchange, an operator's switchboard, a trunk line extending from said automatic exchange to said switchboard, a ringing current response device associated with said trunk line at said switchboard, means for operating one of the switches in the automatic exchange to complete a derived ringing circuit over the trunk line to operate the ringing response device at the operator's switchboard, and a ring cut-off relay included in said circuit for interrupting 115 said circuit.

120 2. In a telephone system, an operator's switchboard, an automatic exchange, a trunk line extending from said exchange to said switchboard, a ringing response device asso- 130

ciated with said trunk line at said switchboard, means for operating one of the switches in said automatic exchange to complete a ringing circuit over a line wiper of said switch and a talking conductor local to the automatic exchange and including a derived circuit of said toll line to operate the ringing response device at the operator's switchboard, a ringing current switching relay in the automatic exchange, a ring cut-off relay in said switch having a winding included in a circuit with the other line wiper of the switch, and means operated upon the response of the operator at said switchboard for closing a direct current circuit over the derived portion of said trunk line to operate said ringing current switching relay to disconnect the local talking conductor from the derived circuit and to connect it instead to a conductor of said trunk line, the latter operation completing a circuit over the trunk line and including the two line wipers of the said switch in series for operating the said ring cut-off relay.

3. In a telephone system, an operator's switchboard, an automatic exchange, a trunk line extending from said switchboard to said exchange, a switch control circuit extending from the said operator's switchboard over the trunk line to the automatic exchange, means under the control of the operator for operating a train of switches in the automatic exchange over the said control circuit to establish a connection with a called line, means at the operator's switchboard for momentarily increasing the current flow over the control circuit, and means in the automatic exchange initially responsive to this momentary increase in current flow for applying ringing current to the called line, said means being operable thereafter independent of any flow of current over the control circuit.

4. In a telephone system, a connector switch, means for operating said switch to extend a connection to a desired line, a relay in said connector switch, a control conductor extending to said switch, means for operating said relay over said control conductor prior to the completion of the operation of said switch, means operated subsequent to the completion of the operation of said connector switch for altering the connection between said control conductor and said relay, and means controlled from the calling switchboard to apply a potential to said control conductor to bring about the de-energization of said relay to project ringing current out over the called line.

5. In a telephone system, a connector switch, means for operating said switch to extend a connection to a desired line, a ringing-current-control relay in said connector switch, a supervisory-control relay, a con-

trol conductor extending from said supervisory-control relay to said ringing-current-control relay, a circuit for operating said ringing-current-control relay over said control conductor prior to the operation of said switch, means operated responsive to the operation of said connector switch for altering the connection between said control conductor and said ringing-current-control relay, a circuit for operating said supervisory-control relay over said control conductor, said circuit rendered effective by said alteration, and means controlled from the calling switchboard to apply a potential to said control conductor to bring about the de-energization of said ringing-current-control relay to project ringing current out over the called line.

6. In a telephone system, an operator's switchboard, an automatic exchange, a trunk line extending from said switchboard to said exchange, a switch in said automatic exchange, means controlled over said trunk line from said switchboard for operating said switch to extend a connection to a called line, a switching relay in said switch operated responsive to an idle condition on the called line, a marginal relay associated with said trunk line, a circuit for said marginal relay excluding the talking conductors of said trunk line, means for setting up a current flow over said circuit insufficient to operate said relay, contacts on said switching relay for increasing the current flow over said circuit to operate said marginal relay, and circuit connections controlled by said marginal relay for giving the calling operator a distinctive indication of the idle condition of the called line.

7. In a telephone system, an operator's switchboard, an automatic exchange, a two-way trunk line between said switchboard and said exchange, switches in the automatic exchange whereby the operator may set up a connection over the trunk line to a called line in the automatic exchange and whereby a calling subscriber at the automatic exchange may set up a connection over the said trunk line to the operator, a supervisory signal at the operator's switchboard operated steadily in either case when the connection is finally established, and means for operating said signal intermittently in either case responsive to the subscriber in the automatic exchange replacing his receiver.

8. In a telephone system, a trunk line extending from an operator's switchboard to a selector, a connector, a circuit superimposed on said trunk line for controlling said switches to extend the trunk line to a called line, a line relay in said circuit at the selector by means of which such control is effected, a marginal relay in series with said line relay, said marginal relay being non-

- responsive to normal current flow in said circuit, operator controlled means for increasing the flow of current in said circuit after the connection is established in order 65
 5 to operate said marginal relay, and ringing equipment in said connector controlled by said marginal relay.
9. In an automatic switch having means for signalling over a connected line, a ring 10 cut-off relay, a ringing control conductor incoming to said switch, and circuit connections such that if said conductor is connected to a source of current before the switch is operated the relay will be energized while 15 if such connection is made after the switch is operated the relay will be deenergized.
10. In an automatic switch having means for signalling a connected line, a ring cut-off relay, a ringing control conductor incoming to said switch, and circuit arrangements in said switch such that said relay is energized and deenergized by successive applications of the same potential to said conductor. 20
- 25 11. In a telephone system, means including a selector and a connector for extending a connection to a called line, a ringing control conductor extending between said switches, means in said selector for automatically and momentarily grounding said conductor when the selector connects with the connector, and a locking ring cut-off relay in said connector energized over said conductor when the same is grounded.
- 30 35 12. In a telephone system, means including a selector and a connector for extending a connection to a called line, a ringing control conductor extending between said switches, means in said selector for automatically and momentarily grounding said conductor when the selector connects with the connector, a locking ring cut-off relay in said connector energized over said conductor when the same is grounded, means in said selector subsequently controlled at the will of the calling party for again grounding said conductor, and circuit arrangements in said connector such that when said conductor is again grounded it will cause said relay to be deenergized. 40 45 50
- 55 13. In a telephone system, a trunk line comprising two sections, an automatic switch for connecting with said trunk line and for transmitting ringing current over the two sections thereof in serial relation, a ring cut-off relay in said switch, a circuit for said relay including a conductor of only one of said sections, and a relay controlled over the other section for closing said circuit.
- 60 65 14. In a telephone system, a trunk line comprising two sections, an automatic switch for connecting with said trunk line and for transmitting ringing current over the two sections thereof in serial relation, a ring cut-off relay in said switch, controlled over one of said sections only, and a second ring cut-off relay at the junction of said sections controlled over both of said sections. 70
- 75 15. In a telephone system, a ringing circuit having two branches both normally open, means for closing the first branch and for applying ringing current to said circuit, means for opening the first branch and for closing the second branch, and means in the second branch for stopping the application of ringing current to said circuit. 80
- 85 16. In a telephone system, a ringing circuit having two branches both normally open, means for closing the first branch and for applying ringing current to said circuit, means in said first branch for opening said first branch and for closing said second branch, and means in said second branch for stopping the application of ringing current to said circuit. 85
- 90 17. In a telephone system, a ringing circuit having two branches both normally open, means for closing the first branch and for applying ringing current to said circuit, a relay energized over said first branch for opening said first branch, contacts on said relay for closing the second branch, and a ring cut-off relay in said second branch. 95
- 100 18. In a telephone system, a trunk line connecting two points, a signal normally connected to said trunk line at the first point and an automatic switch at the second, a circuit superimposed on the two talking conductors of said trunk line, means at the said first point for transmitting current impulses over said circuit to operate said switch, means for transmitting ringing current over said circuit to operate said signal, and means for disconnecting said signal from said trunk line while current impulses are transmitted over said circuit. 105
- 110 19. In a telephone system, a ground return switch control circuit, means for transmitting switch operating impulses over said circuit in one direction, means for transmitting ringing current over said circuit in the other direction, and a ring-cut-off relay included in said circuit during the transmission of ringing current. 115
- 120 20. In a telephone system, a grounded signalling circuit comprising two sections, one section consisting of a talking conductor and the other section consisting of two talking conductors in parallel, a non-talking conductor connecting said sections, and means for transmitting ringing current over said circuit. 120
- 125 21. In a telephone system, a grounded signalling circuit comprising two sections, one section consisting of a talking conductor and the other section consisting of two talking conductors in parallel, a non-talking conductor connecting said sections, means for

ringing over said circuit, and a ring cut-off relay included in said non-talking conductor.

22. In a telephone system, an automatic exchange, an operator's switchboard, a trunk line extending from said automatic exchange to said switchboard, a ringing current response device associated with said trunk line at said switchboard, means for operating one of the switches in the automatic exchange to complete a derived ringing circuit over the trunk line to operate the ringing response device at the operator's switchboard, and means for automatically and intermittently opening and closing said circuit thereafter while the said switch is maintained operated.

23. In a telephone system, an automatic exchange, an operator's switchboard, a trunk line extending from said automatic exchange to said switchboard, a ringing current response device associated with said trunk line at said switchboard, means for operating one of the switches in the automatic exchange to complete a derived ringing circuit over the trunk line to operate the ringing response device at the operator's switchboard, means for automatically and intermittently opening and closing said circuit thereafter while the said switch is maintained operated, and means for automatically stopping the ringing operation when the call is answered.

24. In a telephone system, means including a trunk line for establishing a connection between an operator's position and a called line, said connection being maintained intact by reason of a continuous flow of current over the two conductors of said trunk line in parallel, and means responsive to an increased flow of current in said conductors for signalling the called subscriber.

25. In a telephone system, a connector switch, means for establishing a connection with said switch, a ring control relay in said switch, a supervisory control relay, a ring control conductor, a circuit including said ring control relay, said supervisory control relay and said ring control conductor in series closed by the establishment of said connection for operating said ring control relay, means for operating said connector to connect with a called line, means responsive to the establishment of the connection with the called line for increasing the current flow in said conductor to operate said supervisory control relay, means controlled by said supervisory control relay for interrupting said current flow, and means for reestablishing a current flow in said conductor to deactivate said ring control relay to apply ringing current to the called line.

26. In a telephone system, a connector, a first selector, a second selector, means for establishing a connection via said first selector and said connector to a called line, and means for establishing a connection via said

second selector and said connector to the called line, means in said connector for automatically signalling the called party operative responsive to the completion of the said first connection to the called line, means in 70 said connector operative responsive to the seizure of said connector by said second selector for disabling said automatic signalling means, and means in said second selector for rendering said automatic signalling means 75 effective operative at will upon completion of the said second connection.

27. In a telephone system, a trunk line, a connector for extending a call over said trunk line, signalling means in said connector effective when the call is extended to signal over said trunk line, a ringing current switching relay for said trunk operative when the call is answered to interrupt the signalling, and a ring cut-off relay in said 85 connector responsive to the operation of said ringing current switching relay for completing the talking connection.

28. In a telephone system, a trunk line, an incoming branch normally connected to 90 said trunk line, an outgoing branch normally disconnected from said trunk line, a connector for extending a call over said trunk line via said outgoing branch, a switching relay for said trunk operative when the call is answered for disconnecting said incoming branch from said trunk line and for connecting said outgoing branch thereto, and a relay in said connector responsive to the operation of said switching relay for 100 completing the talking connection.

29. In a telephone system in which connections to a called line are established by automatic switches controlled over the calling line by successively interrupting a normal flow of current over the two talking conductors of the calling line in parallel, means 105 for changing the value of said normal flow of current, and means responsive to said change of value of the normal flow of current for signalling over the called line.

30. In a telephone system, a line, a trunk comprising two talking conductors, means for establishing a current flow over said two talking conductors in parallel, a switch for 115 extending a call to said line controlled over said trunk, means for changing the value of the said current flow, and means responsive to said change for signalling over said line.

31. In a telephone system, a line, means including a selector, a trunk, and a connector, terminating said trunk for extending a connection to said line, means for establishing a current flow over one of the conductors of said trunk, means in the connector operative providing the line is idle when connection thereto is extended for increasing the value of the flow of current over said conductor, a signal, and means in said selector 125 130

responsive to said increase in the value of said current flow for causing the operation of said signal.

32. In a telephone system, a line, means including a trunk comprising talking conductors and a non-talking conductor and a switch for extending a connection to said line, means for establishing a current flow over the non-talking conductor of said trunk, means operative providing the line is idle when connection thereto is extended for changing the value of the flow of current over said non-talking conductor, a signal, and means in said switch responsive to said change in the value of said current flow for causing the operation of said signal.
33. In a telephone system, a line, an operator's switchboard, means for extending a call from said switchboard to said line, a signal at said switchboard, means for operating said signal steadily when the call is answered, and means for operating said signal intermittently when the call is terminated.
34. In a telephone system, a line, an operator's switchboard, means for extending a call from said switchboard to said line, a signal at said switchboard, means for operating said signal intermittently after the call is extended, for operating said signal steadily when the call is answered, and for again operating said signal intermittently when the call is terminated.

35. In a telephone system, a line, means including a trunk for extending a connection to said line, signalling means for signalling over said line normally effective as soon as connection to the line is completed, means for successively applying a potential to one of the conductors of said trunk, and means which is responsive to one application for disabling said signalling means and is disabled by the next application so that said signalling means becomes effective after said next application.

36. In a telephone system, a line, means including a selector, a trunk, and a connector terminating said trunk for extending a connection to said line, signalling means for signalling over said line normally effective when connection to the line is completed, means in said selector for successively applying a potential to one of the conductors of said trunk, and means which is responsive to one application for disabling said signalling means to prevent signalling over the line from taking place when connection thereto is completed, and is disabled by the succeeding application so that said signalling means becomes effective after said succeeding application.

In witness whereof, I hereunto subscribe my name this 27th day of February, A. D. 1925.

JOHN WICKS.
